CLAIM

The ornamental design for a film applicator, as shown and described.

DESCRIPTION

FIG. 1 is a perspective view of a film applicator showing my new design.

FIG. 2 is a front view of a film applicator.

FIG. 3 is a rear view of a film applicator.

FIG. 4 is a right side view of a film applicator.

FIG. 5 is a left side view of a film applicator.

FIG. 6 is a top view of a film applicator.

FIG. 7 is a bottom view of a film applicator; and,

FIG. 8 is another perspective view of a film applicator.

The broken lines throughout the drawing figures depict portions of the film applicator that form no part of the claimed design.
